INVENTOR
Richard Max Eaton
BY
Fred C. Fischer
ATTORNEY

UNITED STATES PATENT OFFICE.

RICHARD MAX EATON, OF NIAGARA FALLS, NEW YORK.

FOCUSING HAND SEARCHLIGHT.

Application filed December 24, 1921. Serial No. 524,600.

To all whom it may concern:

Be it known that I, RICHARD MAX EATON, a citizen of the United States and a resident of Niagara Falls, in the county of Niagara, State of New York, have invented certain new and useful Improvements in Focusing Hand Searchlights, of which the following is a specification.

The predominating object of this invention is to provide an electric searchlight with means for focusing the lens with respect to the lamp bulb, in a manner enabling the user to project rays of light upon distant objects, as often required by motorists in reading signs on roads, house numbers, etc., by policemen, hunters, campers and others who have found the ordinary flashlights to be deficient in range of light projection.

Another object is in the means provided by which the bulb carrying head may be removed from the casing, facilitating the removal of the battery without danger of damaging the bulb or disturbing the focal adjustments.

A further purpose is in the provision of means for readily removing the reflector when exchanging lamp bulbs, thus preventing damage to the reflecting surface.

A still further object is to furnish means by which extra bulbs may be safely carried within the casing until required.

These and other like objects are attained by the novel construction and arrangement of parts hereinafter described and shown in the accompanying drawings, forming a material part of this disclosure, and in which:

Figure 1 is an elevational view showing the flashlight assembled.

Figure 2 is a perspective view showing the relation of essential parts.

Figure 3 is a transverse partial sectional view of the bulb carrying head.

Figure 4 is a sectional view of the bulb contact disc, taken on the line 4-4 of Figure 3.

Figure 5 is a top plan view of the battery holding spring assembled to the lower cover.

Figure 6 is a partial sectional view taken on line 6-6 of Figure 5.

Referring to the drawings in detail, the numeral 10 designates a hollow cylindrical casing of fibre, rubber or the like, having a thin metal ferrule 11 secured at the lower end, provided with coarse pitch screw

threads engageable with a similarly threaded cover 12, having a knurled bead 13 at the bottom adjacent the thread.

A container 14 consists of a pair of annular shells 15 and 16 slidably engaged one with the other, and interiorly of the container, adjacent the bottom of the inner shell 15, is a U-shaped spring clip 16' adapted to resiliently hold an extra lamp bulb 17 which can be substituted for the bulb in use in an emergency.

A spring 18 supports a concave annular disc 19 of greater diameter than the inside of the cover 12, preventing metallic contact with the casing cover, and a tubular rivet 20 provides means by which the elements 15-16-18 and 19 are concentrically held in the cover.

Formed integrally with the top portion of the shell 16 are a plurality of raised clip elements 22 engaging in their openings 23, the terminating base coil of a conical spirally wound compression spring 24.

Secured to the upper or opposite end of the casing 10 is another ferrule 25 screw-threaded along its outer portion, as at 26, and provided with a locking means consisting of an inturned flange 27, slotted as at 28, and having diagonally opposite flange 29 elements 29 turned down eccentrically with respect to the outside of the ferrule ring.

Engageable with the above described member, in the manner of a bayonet lock, is an annular fibre plate 30 having a pair of radial slits 31, their diagonally opposite corners 32 being bent downward into position to pass under the flanges 27.

A metallic lamp holder 35, having a reduced step 35', is secured to the underside of the plate 30 by tubular rivets 36 the step 35' passing upward through an unthreaded opening formed in the plate 30 and has an inturned bead 37 adapted to engage the outside of a screw-threaded lamp socket ferrule 38.

Frictionally held in the large step 39 of the lamp holder, are a pair of fibre insulating plates 40 and 41, each being provided with concentric annular openings, the opening in the plate 40 being receptive of the contact end 42 of a lamp 45.

A spring contact 46, engageable with the contact end of the lamp, is secured at one end to the underside of the plate 40.

Within the opening, in the adjacent fibre plate 41, is a metal shell 48 having a flange

49 engaging the contact spring 46. The extending end of the shell 48 is contactable with a terminal 50 of a dry cell flashlight battery 52, engaged within the body casing 5 10, and forced into contact with the shell 48 by the conical spiral spring 24 acting against the lower or bottom end of the battery.

10 An annular metallic lamp head casing, 15 having a screw-threaded neck 60, is engaged with the flanged ferrule 25, and has a knurled bead 61, adjoining which is an arcuately expanded annular shell 62 having a bottom opening, its edge being re-entrantly turned forming a bead 63 adapted to be securely clinched to the knurled bead 61.

20 A flange element 64 at the upper part of the shell 62 supports a band insulator 65 inter-adjacent the screw-threaded element 66.

25 Interiorly of the casing is a concave parabolic reflector 68, having a burnished silver reflecting surface and provided with an opening at its axial end adapted to engage with the element 35' of the lamp holder. The front edge of the reflector is prevented from contact with the metal casing by the insulating band 65.

30 A concavo-convex lens 70 rests upon the reflector and insulating collar and is secured to the lamp head by a retaining ferrule 72 engaging the screw threaded element 66.

35 A switch frame 75 is secured to the body casing 10 by rivets 76 and has a central sliding member 77 engaged therewith and connected interiorly with a longitudinally disposed, current carrying bar 78, offset at one end and adapted to conduct current from the lamp holder 39.

40 Another current conducting bar (not shown) is connected interiorly of the casing by one of its ends to the lower portion of the switch 75, the end being adapted to make contact with the outer portion of the lamp container 16.

45 From the foregoing it will be seen that the flow of electrical current to and from the battery is conducted in such manner as to prevent short circuiting and premature discharge of the battery or burning out of the bulb by accidental contact with metal bodies as frequently happens with lamps of ordinary construction.

50 By reference to Figure 3 it will be seen by removing the lens ring 72 and the lens 70, the reflector may be removed from the head without interfering with the bulb or disarranging the focal adjustment of the lens.

55 60 It has been found desirable to construct a flashlight that has means by which the focal distance between the lens and the lamp may be increased in a manner adapted to concentrate and project light rays over distances greater than the usual lamp is

capable of projecting. This feature is accomplished by the simple operation of holding the ferrule 25 from turning and rotating the lamp head, thus unscrewing the head from the ferrule 25 a greater or less amount 70 according to the length of rays desired.

75 It will also be seen that if a wide, broadcasting light be required the head may be entirely removed leaving the bulb uncovered and the lamp used as a candle stick.

80 The path of electric current through the lamp structure begins at the battery terminal 50, passes thru the shell 48, thru the spring contact 46 into the bulb terminal end 42, and thru the bulb in the usual manner.

85 The out flowing current passing through the socket ferrule 38 into the lamp holder elements 35', 35 and 39, to the switch conductor bar 78, connected to the sliding switch element 77 of a fixed switch 75, to which is attached a spring conductor contactable with container 16, from which the current is conveyed back to the battery through the conical spring 24.

90 Consideration of the arrangement of insulation and current carrying elements discloses no means by which a short circuit can occur between any two external metal elements of the device.

95 While certain preferred embodiments of this device have been shown and described, it will be understood that changes in the form, arrangements, proportions, sizes and details thereof, may be made without departing from the scope of the invention as 100 defined by the appended claims.

Having thus described my invention, what I claim as new and desire to secure by Letters Patent, is:—

105 1. In a focusing flashlight, the combination with a casing having a removable head, a lamp, a parabolic reflector and a concavo-convex lens, of a ring securing said lens on the head, a battery disposed in the casing, a container insulated from the cap, means within the container for holding an extra bulb, a spring associated with the container for holding the battery in contact with a lamp, a make and break sliding switch, and means within the casing associated with said switch whereby current flowing from said battery may be conducted to said lamp.

110 2. In a focusing flashlight, the combination with a casing, a cover removably engaged with the casing, a spring cushioned shell resiliently attached to said cover, an outer shell slidably over said cushioned shell, a spiral cone shaped spring extending into the casing, means for securing said spring to the top of said outer shell, and means between said shells adapted to secure an extra bulb therein.

115 3. In a focusing searchlight, the combination with a body casing, of an adjustable focusing lens head removably engaged with

the casing, an insulated lamp holder secured at one end of said casing, a removable cap engaged at the other end, a container resiliently fixed in the cap, means for insulating said container from said cap, a compression spring fixed to the container, a battery interposed between the spring and said lamp holder, means for conveying electrical energy from the lamp holder to the container, and a switch engaged with the casing for interrupting or continuing the flow of electrical energy by selective manipulation.

4. In a focusing searchlight, the combination with a body casing, of a lamp head adjustably engaged with the casing, a lamp holder insulated from said head, means for engaging a lamp within the holder, a spring contactable with the lamp, a flanged shell conveying current between said spring and a battery terminal, means in said shell

whereby the lamp is protected from damage by impact, and means whereby the lamp holder may be removed if wedged by swelling of the battery.

5. In a focusing flashlight, the combination with a casing, a cover removably engaged with the casing, an elastic means carried by the cover for resiliently holding and securing an extra bulb therein, and a spiral cone shaped spring having a base of larger diameter than the length of the bulb and means for positioning the base of the spring with relation to the cover so that the axis of the spring is in substantial alignment with the bulb securing means.

This specification signed and witnessed this eleventh day of December, 1921.

RICHARD MAX EATON.
